UNITED STATES PATENT OFFICE.

FRANK B. COOK, OF CHICAGO, ILLINOIS, ASSIGNOR TO FRANK B. COOK COMPANY, OF CHICAGO, ILLINOIS, A CORPORATION OF ILLINOIS.

RELAY.

1,185,371.

Specification of Letters Patent. Patented May 30, 1916.

Application filed December 14, 1914. Serial No. 877,125.

To all whom it may concern:

Be it known that I, FRANK B. COOK, a citizen of the United States, residing at Chicago, in the county of Cook and State 5 of Illinois, have invented a certain new and useful Improvement in Relays, of which the following is a full, clear, concise, and exact description, reference being had to the accompanying drawings, forming a part 10 of this specification.

My invention relates to relays and has for one of its objects the provision of improved means for adjusting the normal or idle positions of floating spring contacts and has 15 for another of its objects the provision of an improved armature structure portion that engages the spring mechanism for actuating it.

As is well known to those skilled in the 20 art, the normal distance between complementary contacts of a relay has been determined by bending the floating contacts or the backing springs thereof, a process which is slow and uncertain.

25 In accordance with one object of my invention I provide a bodily movable abutment for each floating spring contact, the set of the spring contact that is to be adjusted being such as to enable this contact 30 to follow the abutment in its movement of adjustment whereby the position of this spring may readily be determined merely by changing the position of the abutment. In the preferred embodiment of this feature 35 of the invention the abutment is in threaded connection with a threaded shaft that extends transversely of the springs, the position of the abutment being readily changed thereby by turning it upon its shaft. In 40 order to insure the adjusted position of the abutment I provide a locking device which includes interengaging portions carried by the floating spring contact and the adjustable abutment therefor. There are relays 45 which include a plurality of sets or pairs of contacts pertaining to different circuits and I adapt my invention to such relays by elongating the threaded shaft and providing thereupon as many abutments as there 50 are floating spring contacts, one abutment for each of such contacts.

In order to actuate the spring mechanism I provide a wedge or cam upon which a portion of the spring structure is adapted

to ride to effect the movement of those 55 springs that is to be occasioned as a consequence of the energization of the relay. The armature structure also carries another wedge symmetrically arranged with respect to the first and whose function is to be engaged by the spring structure to limit the extent to which the armature may be retracted.

I will explain my invention more fully by reference to the accompanying drawing 65 showing the preferred embodiment thereof and in which—

Figure 1 is a longitudinal sectional view; Fig. 2 is a plan view of the structure appearing in Fig. 1, certain parts being 70 omitted for the sake of clearness; Fig. 3 is a front view of the structure; Fig. 4 illustrates the threaded shaft and a plurality of 75 adjustable abutments mounted thereupon; and Fig. 5 illustrates the interrelation of the armature structure and the spring mechanism whereby the armature may operate the spring mechanism and may be limited in its retractile movement.

Like parts are indicated by similar characters of reference throughout the different figures.

The electro-magnet of the annunciator may be of any suitable or preferred construction, the annunciator shown including 85 a magnetic core 1, a magnetic yoke 2, an armature 3 mounted upon the forward end of the yoke 2, and a winding 4 disposed between the spool heads 5, 6 that are located upon the ends of the core. The yoke 2 also 90 supports a plurality of sets of spring contacts which include master spring contacts 7, 8, 9, and 10 which are respectively provided with complementary and floating contacts 11, 12, 13, 14, 15 and 16. The yoke 2 is also illustrated as carrying winding circuit terminals 17, 18, 19 and 20, two pairs being required if the winding of the relay is made up of two coils, though the number 95 and disposition of these circuit terminals are immaterial so far as my invention is concerned. The yoke 2 also carries an arm 21 upon the forward end of which is fixedly secured a threaded shaft 22 located near the contacting ends of the springs 11, 12, etc. 100 Abutments 23 are in threaded connection with the shaft 22, there being one abutment for each of the floating contacts. As the 105

shaft 22 is disposed transversely of the springs the normal or idle position of the floating contacts is determined by positioning the abutments with respect thereto, the 5 set of the springs being such as to enable them to maintain constant engagement with their abutments throughout the normal range of adjustment of the latter. While the abutments are shown as being adjustable 10 transversely of the floating contact springs taken integrally, yet, it is obvious that the transverse movement of the abutments is required only with respect to the portions of the floating contact springs that they 15 engage. Thus the relative positions of each set of floating and master contacts may be very quickly and accurately determined. In order to insure the maintenance of the adjusted positions of the abutments they are 20 desirably made in the form of disks in each of which there is provided a peripheral row, of holes 24 which are adapted to receive projections 25 formed in the floating contacts. The peripheries of these disk abutments may 25 be grooved or knurled to facilitate the turning thereof.

The master contacts 8 and 9 carry cam rollers 26 and 27 at their forward ends, these rollers being upon opposite sides of an 30 actuating cam 28 mounted at the upper end of the armature structure and desirably in the form of a cone. Whenever the armature is actuated the base of the cam cone 28 is moved toward the rollers 26 whereby these 35 rollers are spread apart to actuate the master contacts 8 and 9. The master contacts 7 and 10 also carry rollers 29 and 30 which engage the master contacts 8 and 9 whereby the master contacts 7 and 10 are spread 40 apart when the master contacts 8 and 9 are spread apart. The armature structure also carries a cam 31 which is symmetrically arranged with respect to the cam 28 and is also desirably cone shaped, these two cams 45 being preferably co-axial, the cam 31 by engaging the rollers 26 serving to limit the

extent to which the armature may be retracted when the relay is de-energized.

While I have herein shown and particularly described the preferred embodiment 50 of my invention I do not wish to be limited to the precise details of construction shown as changes may readily be made without departing from the spirit of my invention, but

55

Having thus described my invention I claim as new and desire to secure by Letters Patent the following:

1. A relay including floating and master contacts; a bodily transversely movable 60 abutment for the floating contact to determine its normal position; and a holding device for maintaining the abutment in adjustment which includes interengaging formations provided upon the abutment and 65 the floating contact.

2. A relay including its armature; switching mechanism to be operated by the armature; and symmetrically related cams carried by the armature and between which 70 the switching mechanism is engaged, one cam for operating the switching mechanism and the other for enabling the switching mechanism to limit the retractile movement of the armature.

75

3. A relay including its armature; switching mechanism to be operated by the armature; and symmetrically related co-axial conical cams that slope toward each other with both of which the switching mechanism is engaged, one cam serving to operate the switching mechanism and the other serving to enable the switching mechanism to limit the extent to which the armature may be retracted.

85

In witness whereof, I hereunto subscribe my name this first day of December, A. D. 1914.

FRANK E. COOK.
